METALLIC PILING

Gerald G. Greulich, Mount Lebanon, Pa.

Application December 29, 1937, Serial No. 182,354

1 Claim. (Cl. 61—53)

The present invention relates to metallic piling. An object of this invention is to provide a metallic pile made from preformed relatively light gage sections.

5 Another object is to provide a piling shell possessing sufficient strength to withstand the driving force necessary to position the pile in place.

Other objects and advantages will become apparent as the description proceeds, in which:

10 Figure 1 is a sectional elevation of the present invention showing the piercing point and driving ring in position;

Figure 2 is a section on the line II—II of Figure 1;

15 Figure 3 is an elevational view showing another manner of forming the piling shell;

Figure 4 is a section on the line IV—IV of Figure 3;

20 Figure 5 is an elevational view similar to Figure 1 but showing the piling shell tapered; and

Figure 6 is a top plan view of Figure 5; and

25 Figure 7 is a section on the line VII—VII of Figure 6.

In the drawing, the metallic piling includes preformed complementary sections 2 of any desired cross-sectional shape, suitably welded, in any conventional manner, along their edges. Under the present invention, light gage materials are preformed, as desired, by an ordinary cold rolling process. These preformed complementary sections 2 are provided with reinforcing ribs 3 extending longitudinally from one end of said piling shell to the other while, if desired, transverse reinforcing ribs 4 may be provided intermediate 30 certain of the longitudinal ribs, as shown in Figure 3.

The preformed complementary sections 2 have their edges overlapped, as shown in Figures 2, 6 and 7, and welded in conventional manner by an automatic seam welder or, if desired, said sections 2 may be provided with laterally extended flanges 5, as shown in Figures 3 and 4, in which case the welding of said sections along the contact surface of said flanges may be accomplished by the conventional spot-welding method. In either case, the preformed complementary sections 2 are assembled into a unitary shell to which is secured, upon one end, a piercing point 6.

The piercing point is preferably a cast member

having a tapered conical point in order to provide a self-centering action during driving of said piling shell into proper position. An annular flange 7 is provided upon the inner wall of said piercing point to support and retain said complementary sections forming the piling shell upon said point 6. The ends of said complementary sections are welded, in any conventional manner, to the piercing point 6.

In forming the piling shell from relatively light gage stock, it is necessary to protect the top edges of said complementary sections during the driving of said piling shell into proper position. In order that the piling shell will withstand the impulses received during driving, a metallic ring 8 is inserted within the inner wall of said piling shell and provided with a flange 9 extending laterally to a point slightly beyond the ribs 3. This ring may be welded, in any conventional manner, to the end of said piling shell.

There is shown a straight cylindrical piling shell in Figures 1 and 3. If desired, the piling shell may be tapered toward the piercing point 6, as shown in Figure 5.

While I have shown and described specific embodiments of the present invention, it will be understood that I do not wish to be limited exactly thereto, since various modifications may be made without departing from the scope of the invention, as defined by the following claim.

I claim:

A tubular metallic pile comprising a plurality of complementary arcuate sections welded together to provide a hollow chamber, said arcuate sections provided with spaced longitudinally arranged reinforcing corrugations and transverse corrugations between certain of said longitudinal corrugations, a piercing point welded to the bottom portion of said hollow chamber and an annular protective driving ring welded to the upper portion of said hollow chamber and positioned within the bore thereof and including a laterally extending flange extending over the top edge of said pile and terminating in substantial alignment with said corrugations whereby said pile withstands the impact of the blows during driving of said pile in position.

GERALD G. GREULICH.
